SHOULDER PAD

Florence B. Zacks, Columbus, Ohio, assignor to
 R. G. Barry Corporation, Columbus, Ohio, a
 corporation of Ohio

Application July 30, 1948, Serial No. 41,451

6 Claims. (Cl. 2—268)

1

This invention relates to shoulder pads and has for its general object the provision of novel and improved shoulder pads for women's wear which are adapted to square up the shoulders of the garments to a more or less degree according to the prevailing mode, and which are removable from the shoulder independently of the garment, thus facilitating laundering of both the garment and the pad.

Within the scope of the invention, the pads 10 may be stuffed with sponge rubber or batting of cellulosic or other origin pre-molded, at least to some extent, to fit the crown of the shoulder and preferably to taper to a desired degree from the maximum thickness at the outer margin to a minimum at the innermost point nearest the neck.

Each of the novel pads are provided with a pair of securing straps—preferably of elastic tape material—upon its underside—one upon the forward half and one upon the rearward half. These straps are permanently secured to the pad at one end and detachably secured at the other end as by means of a snap-fastener, and are adapted to frictionally embrace the shoulder strap of the slip, the brassière, or other undergarment of the wearer, and are thus attached and removed entirely independently of the garment to which they are designed to lend shape.

One of the principal features of the present invention is the provision—in connection with the securing elastics—of stiff although somewhat resilient reinforcing and tension-resisting strips or "bones." These strips may be of steel, whalebone, plastic, composition, or other suitable materials, and are contained within the fabric covering of the pads alongside of or embedded in the filler or stuffing. The bones are disposed parallel with the securing elastics and are secured to the pad preferably by rivets, staples, or other fastening elements which may pass entirely through the pad and which may also serve to secure the elastics and one of the snap-fastener elements.

The stiffening strips or bones serve not only to reinforce the pad and aid in preserving its shape 45 at all times, but they are especially useful in preventing the pads collapsing or buckling transversely under the tension of the securing straps or elastics.

Other objects and features of novelty will be apparent from the following specifications when read in connection with the accompanying drawings in which certain embodiments of the invention are illustrated by way of example.

In the drawings:

2

Figure 1 is a fragmentary view in perspective showing a pad embodying the principles of the invention and applied to a shoulder;

Figure 2 is a plan view of the underside of a pad flattened out in a single plane, the pad in this example being stuffed with sponge rubber.

Figure 3 is a fragmentary sectional view of the pad shown in Figure 2, taken on line 3—3 of that figure;

Figure 4 is a view similar to Figure 2 of a pad stuffed with batting of fibrous material; and

Figure 5 is a view similar to Figure 3 of the pad of Figure 4, taken on line 5—5 of Figure 4.

In the drawings the novel shoulder pad is indicated generally by the reference numeral 10 and will be seen to have a generally triangular contour, even approaching semi-circular as the inwardly directed corner is rounded off. The pad when applied assumes a generally inverted U-shaped configuration snugly fitting the shoulder 12 of the wearer and the thicker edge 13 outermost and the attenuated curved edge 14 nearer the neck 15 of the wearer. An undergarment 16 of any conventional type is shown in Figure 1 as having a shoulder strap 17 to which the novel shoulder pad 10 may be anchored to prevent its inadvertent displacement from its proper position upon the crown or arch of the shoulder.

In Figures 2 and 3 of the drawings, there is 30 shown a preferred embodiment of the invention in which the padding or stuffing of the shoulder pad is of molded sponge or "foam" rubber as indicated at 20. This mass of soft rubber is wedge-shaped in transverse section and is of a roughly triangular or semi-oval configuration being enclosed in the covering fabric 21. The covering fabric is conveniently formed of an approximately oval assemblage of cloth which is doubled upon itself along a diameter corresponding to the margin 13 of the pad and the overlapping pinked edges 23 sewed together along the seam 25. The cloth blank of which the covering 21 is made is preferably composed of two parts united along the transverse seam 26.

Upon the under side of the pad and between the sponge rubber filler 20 and covering cloth 21 there is interposed a lining 27 which may be of a fairly coarse somewhat stiff fabric. Interposed between the liner 27 and the sponge rubber 20 and extending diagonally of the pad upon each half thereof, as clearly shown in Figure 2, is the bone or reinforcing strip 30, which may be made of metal, plastic, whalebone, or any suitable or conventional stiff material. At one end of the 55 liner 27, the comparatively rigid strip and the

sponge rubber may be secured together as by means of the staple 32, while the other end of the assembled material, including the covering fabric 21, is pierced by the rivet portion 35 of a snap fastener being carried by the free end 37 of the securing strap 38, the opposite end of which is sewed through the thickness of the pad and the bone or strip 30 so that when not fastened the strap 38 lies in a position shown in the upper portion of Figure 2. Thus when the strap 38, which is preferably of elastic material, is stretched into position around the undergarment shoulder strap 17 so that the snap fastener 35, 36 may be closed, the shoulder strap 17 will be frictionally embraced between the pad proper and the strap 38, with the edges of the shoulder strap 17 confined between the snap fastener 35, 36 and the folded portion 42 of the elastic 38. This arrangement insures that the shoulder strap 17 will be snugly and frictionally received by the pad.

It will also be readily perceived that the bone or reinforcing strip 30 aids in maintaining the proper configuration of the pad, especially along the forward and rear sides of the shoulder, and also resists any transverse deformation of the shoulder pad due to the tension of the elastic securing strap 38.

In Figures 4 and 5 of the drawings, there is illustrated an alternative embodiment of the invention in which substantially the same covering structure is employed, including the fabric 21, but in which the stuffing 20' comprises cotton batting or the like. The bones or reinforcing strips 30' are disposed at the same angular positions as in the earlier stuffing by means of the rivet 21' and the rivet portion 35 of the snap fastener 35, 36. The rivet 21' also serves to secure one end of the elastic supporting strap 38' to the pad. The opposite end 37' of the elastic 38' carries the snap fastener portion 36 which cooperates with the opposite portion 35 to secure the elastic strap 38' in frictional retaining position around the undergarment shoulder strap 17. The reinforcing strip 30' serves the same function in this embodiment in helping to preserve the shape of the pad and resisting deformation due to the tension of the straps 38'.

As used in the claims, the phrase "direction of extent of the shoulder of the wearer" is intended to signify the direction along the ridge of the shoulder from the neck outwardly.

Various changes and modifications may be made in the embodiments illustrated and described herein without departing from the scope of the invention as defined by the following claims.

Having thus described the invention, what is claimed as new and desired to be secured by Letters Patent is:

1. A shoulder pad of the class described comprising, in combination, a covered fabric, a soft yieldable stuffing therein, a pair of separate narrow stiff reinforcing bones embedded in the pad, each bone extending approximately in the direction of extent of the shoulder of the wearer, the bones being spaced apart transversely of the shoulder, elastic retaining tapes applied to the underside of the pad, said tapes being approximately coterminous and parallel with the respective bones, means for securing the respec-

tive ends of the tapes to the body of the pad and to said bones at points adjacent thereto, with the tapes under tension and the intermediate portions thereof embracing the shoulder strap of the undergarment of the wearer.

2. In a shoulder pad of the class described, a soft yieldable body portion a covering fabric, a narrow relatively stiff reinforcing bone embedded in the pad, adapted to extend approximately in the direction of extent of the shoulder of the wearer, and of a length shorter than the extent of the pad in said direction, whereby said bone terminates somewhat short of the ends of the pad, a retaining tape applied to the pad and disposed when in use substantially parallel and coterminous with said bone, means for securing one end of said tape to the pad adjacent the corresponding end of said bone at one point, and means for securing the other end of said tape to the pad adjacent the opposite end of said bone.

3. In a shoulder pad of the class described, a soft yieldable body portion, a covering fabric, a narrow, relatively stiff reinforcing bone embedded in the pad and adapted to extend approximately in the direction of extent of the shoulder of the wearer, a retaining tape applied to the pad and disposed when in use substantially parallel with said bone, means extending at least partially through the body of the pad for securing one end of said tape both to the pad and to said bone at one point, and means for similarly securing the other end of said tape to the pad and to the bone at a point spaced from said first named point.

4. In a shoulder pad of the class described, a soft yieldable body portion, a covering fabric, a straight, narrow, relatively stiff reinforcing bone embedded in the pad and adapted to extend approximately in the direction of extent of the shoulder of the wearer, an elastic retaining tape applied to the pad and disposed when in use substantially parallel with said bone, means extending at least partially through the body of the pad for securing one end of said tape permanently both to the pad and to said bone at one point, and means for detachably securing the other end of said tape to the pad and to the bone at a point spaced from said first named point.

5. The shoulder pad set forth in claim 4 in which the second named securing means comprises a snap fastener combination, one element of which is permanently secured to said bone and the body of the pad and the mating element is secured to the last named end of the tape and is adapted to be snapped into engagement with the first named element.

6. The shoulder pad set forth in claim 4 in which the body of the pad is sponge rubber.
